UNITED STATES PATENT OFFICE.

CHARLES H. HELMER AND JOSEPH WEHRUNG, OF ROCHESTER, NEW YORK, ASSIGNEES
TO FITZ-EMPIRE DOUBLE PIVOT LAST COMPANY, OF AUBURN, MAINE, A CORPO-
RATION OF MAINE.

LAST.

Application filed August 5, 1918. Serial No. 248,473.

To all whom it may concern:

Be it known that we, CHARLES H. HELMER and JOSEPH WEHRUNG, citizens of the United States, residing at Rochester, in the county of Monroe and State of New York, have invented certain Improvements in Lasts, of which the following description, in connection with the accompanying drawings, is a specification, like reference characters on the drawings indicating like parts in the several figures.

The present invention relates to lasts, and in particular to lasts constructed of wood.

Wooden lasts are ordinarily turned with the grain of the wood running longitudinally and with the annual layers of the wood substantially horizontal. This is due partly to the fact that the timber bolts from which the rough last blocks are cut work up more economically if the cone portions of the blocks are turned toward the center, and partly to considerations of strength in the finished last. The line joining the centers on which the last is turned in the last lathe passes through the toe tip and the approximate middle point of the heel end so that in many lasts, particularly those intended for very high-heeled shoes, the annual layer of wood which is tangent to the lowest point of the concave longitudinal curve at the upper surface of the ball will pass beneath the tip of the toe, leaving several disk-like annual layers above it forming the toe tip. The top of the toe then looks like a hill on a contour map. In the use of a last in shoemaking, the inverted last is supported on a standard in several machines (sole laying, leveling, lasting, etc.) which engages it at or near the summit of this "hill" with the result that a violent blow of the leveling roller, for instance, will often split off the upper layer, thus ruining the last.

An even more frequently occurring difficulty is the breaking or splitting off of the entire toe tip by, for instance, the initial blow of the leveling roller, especially in lasts where the grain runs downward and forward at the toe tip, as often happens.

An important object of our invention is the correction of the above described difficulties, and an important feature of the invention is accordingly a novel organization of a last with a reinforcing member

in the top of its toe to protect the upper layers of wood at this point.

This and other features of the invention comprising various combinations and arrangements of parts will be understood from the following description of several embodiments of the invention selected for purposes of illustration and shown in the drawings.

Fig. 1 of the drawings is a plan view of a last toe;

Fig. 2 is a broken-away side view of a last, slotted in accordance with our invention, with the reinforcing member;

Fig. 3 is a similar view showing another form of the slot and reinforcing member;

Fig. 4 shows a broken last toe;

Fig. 5 is a front view of the construction of Fig. 2;

Fig. 6 is a perspective view of the reinforcing member of Fig. 2.

Fig. 7 is a view like Fig. 2 but showing the reinforcing member in place;

Fig. 8 is a similar view relating to the reinforcing member of Fig. 3;

Fig. 9 is a bottom plan of the Fig. 3 construction.

Figs. 1, 2 and 3 of the drawings illustrate a last for a high-heeled shoe. The line of centers of the last lathe is shown at 10. This line is nearly or quite parallel to the grain of the wood. In a last of the type illustrated this line is at a considerable angle with the floor line and therefore the grain layers of the wood outcrop at the top of the toe as shown at 12. The upper layer at 14 is often broken out in the shoemaking operations, particularly those involving a support for the inverted last at this point such as the leveling operation.

Fig. 4 illustrates the second difficulty described. The last there shown had a twist in its grain running downward and forward at the toe tip and was broken by the initial stroke of the leveling roller.

Our invention provides for the correction of these difficulties among others. We preferably form a longitudinal vertical slot centrally in the toe of the last as at 18, and insert in it a piece of hard wood 20 (we have found hickory and persimmon excellent for the purpose), with the grain running preferably parallel to the tread surface as shown by the line 11. The toe supporting posts of the sole laying, lasting and

leveling machines will engage this member and will not have the tendency to split off the contacting portions of it, since its grain runs back into the insert instead of lying parallel to the surface at this point, as it does in the main body of the last. The instrumentalities which strike the sole face of the last, such as the leveling roller, will strike this insert crosswise of its grain and will not be able to shear it off, as is often done to the toe tip of the unreinforced last as shown in Fig. 4.

The inserted piece 20 extends clear through the toe from top to bottom, at its thickest part and thus forms the highest and lowest part of the toe, taking a prominent part in the resistance to compressive stresses exerted on the toe. It also effectively ties together the grain in the toe since its grain runs at a considerable angle with the grain of the main body of the last at this point as shown in Figs. 7 and 8, and thus secures the toe against splitting from any cause.

It has been proposed to insert a round dowel longitudinally into the toe, but this practice does not secure the advantages of our invention. In the first place, the curved surface of the dowel acts as a wedge and tends to split the last toe under certain kinds of stress, and in the second place, it does not tie the fibers together across the toe or protect the upper surface of the toe.

As far as the difficulty of the splitting off of the upper annual layer of wood is concerned, it is not necessary that the reinforcing piece extend to the tread face. It need only be inserted in the top of the toe and have its grain at an angle to that of the wood there.

We have shown two ways of keying the insert 20 into the toe. Figs. 2, 5 and 6 show a double rib near the bottom of the insert 20 which co-operates with a similar pair of slots or mortises in the last toe. Figs. 3, 8

and 9 show a small dowel 24 let into both the toe and the insert 20. The insert will be firmly fastened in position, as by gluing or cementing.

Having described our invention, what we claim as new and desire to secure by Letters Patent of the United States is:—

1. A last having a reinforcing member in the top of its toe, the last and member having registering grooves, and a binder inserted in the grooves.

2. A last having a reinforcing member extending entirely through the toe from one surface thereof to that opposite, the member and the last having registering grooves and a holding member mounted in the grooves.

3. A wooden last having a toe reinforcing member constructed and arranged to tie the wood fibers together transversely entirely across the toe from the top to the bottom of the toe, the member and the last having facing grooves, and a dowel mounted in the grooves.

4. A last having a reinforcing member extending through the toe from one surface to that opposite and a binding member embedded in the joint between the reinforcing member and the main body of the last.

5. A last having a binding member in its forepart extending through the toe from one surface to that opposite, the member and the main body of the last having registering grooves, and a binder inserted in the grooves.

6. A last having a reinforcing member extending entirely through the toe from one surface thereof to that opposite, one of said parts being provided with a groove and the other part with a holding member mounted in said groove.

In testimony whereof we have signed our names to this specification.

CHARLES H. HELMER.
JOSEPH WEHRUNG.
